UNITED STATES PATENT OFFICE.

ARTHUR M. BURNHAM AND HATTIE L. BURNHAM, OF GARDINER, MAINE.

PLATE LIFTER AND TURNER.

SPECIFICATION forming part of Letters Patent No. 558,154, dated April 14, 1896.

Application filed February 11, 1895. Serial No. 537,979. (No model.)

To all whom it may concern:

Be it known that we, ARTHUR M. BURNHAM and HATTIE L. BURNHAM, of Gardiner, in the county of Kennebec and State of Maine, have 5 invented certain new and useful Improvements in Plate Lifters and Turners; and we do hereby declare the following to be a full, clear, and exact description of the invention, such as will enable others skilled in the art 10 to which it appertains to make and use the same.

Our invention relates to an improvement in plate lifters and turners, the object of the invention being to produce simple and 15 cheap devices for lifting and turning a plate while in the oven, such devices being so constructed and arranged that it will be unnecessary to apply the devices to the plate while in the oven, thus avoiding the danger of 20 injuring the pastry in the oven, as is liable to be done when the lifter is applied to the plate while the latter is in the oven.

A further object is to so construct plate lifting and turning devices that it may be applied 25 to a plate before inserting it into an oven and a portion of said devices left connected with the plate.

A further object is to produce plate lifting and turning devices which shall be simple in 30 construction, cheap to manufacture, easy to operate, and effectual in the performance of their functions.

With these objects in view the invention 35 consists in certain novel features of construction and combinations and arrangements of parts, as hereinafter set forth, and pointed out in the claims.

In the accompanying drawings, Figure 1 is 40 a view in elevation of our improved plate-lifter, the handle appearing in perspective; and Figs. 2 and 3 are details.

While we have shown the device in the drawings as applied to a pie-plate, it is evident that it may also be applied to other kinds 45 of cooking utensils.

A represents a plate, to which a frame or bail B is removably connected. The frame or bail B is preferably composed of at least three pieces of wire to constitute arms a, so 50 bent as to have a springing action, so that when they are applied to a plate they will clamp the same. The inner ends of the wire

arms a meet at a point centrally located over the plate A and are twisted together, as at b. A washer or disk c is placed over the end of 55 the twisted portion or stem b and the free ends of the wire bent outwardly, as at i, to retain said disk or washer in place.

The hole c' in the disk is preferably punched with a pointed instrument in order to form 60 the three upturned barbs c² c³, between which the ends i of the wire are bent. The twisted shank b is so short that the wires frequently turn relative to each other if not rigidly secured together. We have devised this means 65 as a simple and convenient one to prevent this turning, the barbs absolutely preventing any turning of the wires.

A rod or handle C is provided at its end with a fork C', by means of which to operate 70 the device. The fork may be made of wire or it may be cast. In either event it has an offset or crook down, as at c⁴, so the handle will not turn in the hand, and the extreme ends c⁵ of the tines turn up, so the bail cannot 75 slip out when carrying a dish. The fork also preferably has a collar or flange c⁶ thereon, which holds the ferrule firmly between it and the handle proper.

In using the devices above described a frame 80 or bail B is applied to each plate to be used before they are inserted into the oven, and are left on the plates while in the oven, and they may also be left on the plates after their removal from the oven. When the plates 85 with the bails B thereon are in the oven and it is desired to lift them for removing them or for turning, the fork C will be made to embrace the stem b of the bail and bear against the washer or disk c, the upwardly-projecting 90 ends c⁵ of the fork preventing the escape of the device therefrom. Thus it will be seen that by means of the handle and fork the pan or plate may be removed from the oven without danger of injuring the pastry contained 95 in other pans or plates, or a pan or plate may be easily turned without disturbing other pans or plates.

Our improvements are exceedingly simple. They may be used without the necessity of 100 applying them to a pan or plate while the latter is in the oven; but, on the contrary, a portion of the devices may be allowed to remain attached to the plate or pan while in the oven.

The devices are cheap to manufacture and effectual in every respect in the performance of their functions.

Having fully described our invention, what we claim as new, and desire to secure by Letters Patent, is—

1. In a plate lifter and turner, the combination with a series of spring-arms twisted together at their upper ends to form a common centrally-located shank, the said shank having a flat rounded enlargement thereon, of a handle having a forked end adapted to constitute a bearing for the flat rounded enlargement to rest and turn upon, substantially as set forth.
2. In a plate lifter and turner, the combination with several spring-arms twisted to-

gether to form a common central shank and a flat circular disk or washer having a central opening formed therein and upturned barbs adjacent to the edges of the central opening between which the extreme upper ends of the spring-arms are bent and held, of a handle having a forked end which receives and constitutes a seat for the disk or washer, substantially as set forth.

In testimony whereof we have signed this specification in the presence of two subscribing witnesses.

ARTHUR M. BURNHAM.
HATTIE L. BURNHAM.
